DFS. 2286

Louis Saarbach, of Philadelphia, Pa,
Letter Patent No. 2286. Dated Mar 27, 1866,

Ante-dated Mar 6, 1866.

Design for a Tobacco Pipe.

The schedule referred to in these Letter Patent & making part of the same

To all whom it may concern:

It is known that Louis Saarbach of Philadelphia County of Philadelphia State of Pennsylvania have invented or produced a new and original design for a Tobacco Pipe and I do hereby declare the accompanying Drawing with the following explanation of the same to form a full, clear and exact description of the said Design.

The figure in the accompanying drawing represents a tobacco pipe.

The bowl A of the pipe is connected to a metal reservoir B, the shape of which resembles that of the head of a bird, as shown in the drawing, the open end of the reservoir being bent upwards to receive the lower end of the stem C.

Claim

The design for a tobacco pipe, substantially as shown in and by the accompanying drawing.

In testimony whereof I have signed my name to this specification in the presence of two subscribing witnesses

Witnesses.
